DESIGN FOR A STOCK TANK HEATER

John K. Newhall, Aurora, Ill.

Application October 5, 1944, Serial No. 115,631

Term of patent 14 years

(Cl. D81—19)

To all whom it may concern:

Be it known that I, John K. Newhall, a citizen of the United States, residing in Aurora, in the county of Kane and State of Illinois, have invented a new, original, and ornamental Design for a Stock Tank Heater, of which the following is a specification, reference being had to the accompanying drawing, forming part thereof.

Fig. 1 is a perspective view of a stock tank heater embodying my new design;

Fig. 2 is a top plan view of the stock tank heater shown in Fig. 1; and

Fig. 3 is an end elevational view of the same.

The deflector at the top of the stack is adjusted to a different position in Figure 1 than in Figs. 2 and 3.

I claim:

The ornamental design for a stock tank heater, substantially as shown.

JOHN K. NEWHALL.
